UNITED STATES PATENT OFFICE.

EDWARDS H. GREIST, OF CHICAGO, ILLINOIS.

DESIGN FOR A SERVICE FLAG, PENNANT, OR SIMILAR EMBLEM.

Application filed July 16, 1917. Serial No. 180,955. Term of patent 3½ years.

To all whom it may concern:

Be it known that I, EDWARDS HAROLD GREIST, a citizen of the United States, residing at 7017 Greenview Avenue, in the city of Chicago, county of Cook, and State of Illinois, have invented a new, original, and ornamental Design for a Service Flag, Pennant, or Similar Emblem, reference being had to the accompanying drawing, wherein is represented an elevation of a pennant embodying my new design.

I claim:

The ornamental design for a service flag pennant or similar emblem as shown.

E. H. GREIST.

Witnesses:

LEWIS T. GREIST,
MARY C. BROWER.
